ATTORNEY

UNITED STATES PATENT OFFICE.

MERCER D. BLONDEL AND JOSEPH A. RYAN, OF WASHINGTON, DISTRICT OF COLUMBIA.

DESIGN FOR A FRAME FOR WRENCHES.

SPECIFICATION forming part of Design No. 27,919, dated November 30, 1897.

Application filed October 22, 1897. Serial No. 656,102. Term of patent 31 years.

To all whom it may concern:

Be it known that we, MERCER D. BLONDEL and JOSEPH A. RYAN, citizens of the United States, residing in Washington city, in the District of Columbia, have invented and produced a new and original Design for the Frame of a Wrench, of which the following is a specification, reference being had to the accompanying drawings, forming part thereof.

10 Figure 1 is a side view, and Fig. 2 is an end view, of our wrench-frame.

The leading feature of our design consists in the body portion 1 of the wrench-frame provided with a lateral opening 2, a laterally-15 curved arm 3, extending from one end of said

body, and a reduced straight extension 4 at the opposite end, the said extensions 3 4 being arranged at diagonally opposite corners of part 1.

A minor feature of the design consists in 20 the upper straight end extension 5 and the ovals or swells 6 of the body 1 of the frame.

What we claim is—

The design for the frame of a wrench substantially as shown and described.

M. D. BLONDEL.
JOS. A. RYAN.
